UNITED STATES PATENT OFFICE.

JOHN DERUS, OF MINNEAPOLIS, MINNESOTA, ASSIGNOR OF ONE-THIRD TO
JOHN GIERET, OF SAME PLACE.

FIRE-ESCAPE.

SPECIFICATION forming part of Letters Patent No. 660,622, dated October 30, 1900.

Application filed June 7, 1900. Serial No. 19,374. (No model.)

To all whom it may concern:

Be it known that I, JOHN DERUS, a citizen of the United States, residing at Minneapolis, in the county of Hennepin and State of Minnesota, have invented certain new and useful Improvements in Fire-Escapes; and I do hereby declare the following to be a full, clear, and exact description of the invention, such as will enable others skilled in the art to which it applies to make and use the same.

My invention relates to fire-escapes, and has for its object to improve the same in the several particulars hereinafter noted.

To such end the invention consists of the novel devices and combinations of devices hereinafter described, and defined in the claims.

The invention is illustrated in the accompanying drawings, wherein like characters indicate like parts throughout the several views.

Figure 1 is a view in front elevation, showing a building equipped with one of my improved fire-escape devices, some parts being broken away and others sectioned. Fig. 2 is a view partly in side elevation and partly in vertical section, some parts being broken away, showing the parts illustrated in Fig. 1. Fig. 3 is a detail in horizontal section approximately on the line $x^3 x^3$ of Fig. 1, some parts being broken away. Fig. 4 is a detail view in side elevation with some parts broken away, showing a portion of one of the vertical tracks and one of the vertically-movable rail-trucks. Fig. 5 is a detail on an enlarged scale in vertical section approximately on the line $x^5 x^5$ of Fig. 1, and Fig. 6 is a detail view showing a pawl-and-ratchet device for holding the windlass-operating shaft.

The numeral 1 indicates in outline a building having doors, windows, and the ordinary arrangement. In the illustration given a small three-story building is shown; but it will of course be understood that this fire-escape is applicable to a building of any sort and is, in fact, especially intended for high office buildings.

In accordance with my invention I provide the building with suitable vertical tracks or guides and for coöperation therewith provide a horizontal rail which is adjustable ver-

tically by suitable mechanism controlled from the bottom of the building or from the sidewalk. A car or cage is mounted to run upon or to be suspended from below a horizontal rail, and this car is preferably detachably secured to small trucks or devices movable over said horizontal rail, so that the car may ordinarily be detached and may, if desired, be carried by the apparatus of the fire department.

The vertical tracks or guide 2 are preferably in the form of channel-bars having in-turned flanges 3. For vertical movement over these tracks 2 small trucks made up of blocks or bodies 4 and wheels 5, mounted thereon, are provided. The truck-wheels 5 run over the outer surface of the flanges 3, while retaining lugs or projections 6 from the blocks or bodies 4 engage the inner sides of said flanges 3 and prevent the said trucks from jumping from the said tracks. To the block 4 of each truck is secured one end of a wire rope 7, which is passed over a guide-sheave 8, mounted at the upper end of the coöperating channel or track 2, and is then passed downward between the flanges of said track and thence over a lower guide-sheave 9, suitably mounted in the bracket 10 beneath the sidewalk 11. The lower ends of the ropes 7 are secured to and wound on windlass-drums 12, both of which drums are rigid on the common windlass-shaft 13, mounted in bearings 14, secured below the sidewalk 11. At one end the windlass-shaft 13 is provided with a beveled pinion 15, which meshes with the coöperating beveled pinion 16, carried at the lower end of a vertically-disposed operating-shaft 17. The shaft 17, as shown, passes upward through the sidewalk 11 and is suitably mounted in a bearing-bracket 18. At its upper end the shaft 17 is provided with a hand crank or lever 19, which is preferably removable and by means of which it may be turned. To hold the windlass drums and shaft against unwinding movements, the operating-shaft 17 is provided with a ratchet wheel 20, with which a foot-released retaining-pawl 21, pivoted to a plate 22, coöperates.

By the connections described the trucks 4 are given equal vertical movements, and these vertical movements thereof serve to

raise and lower a horizontally-extended rail 23, the ends of which are secured to brackets 24, projected from the truck-blocks 4.

The car or basket 25 is suspended from 5 trucks mounted to move over the rail 23. As shown, two small trucks, formed each by a bracket 26 and a pair of flanged wheels 27, are employed for this purpose. The flanged wheels 27 of each truck engage one the upper 10 and the other the lower edge of the rail 23, and thus prevent the trucks from jumping off from the rail. The car or basket 25 is supported from the truck-brackets 26 by chains 28 and 28' or other suitable connection. The chains 28' on the cage are provided 15 with hooks 29, which engage rings or links 30 of the said chains 28 on the bracket 26, so that the said basket or car may be readily detached.

20 A wire rope or other flexible connection which will not burn connects each end of the basket or car 25 to one of the vertically-movable trucks 4 5. These ropes or cables 31 are long enough to permit the car to be moved 25 from one end to the other of the horizontal rail 23, and preferably they are permanently attached to the car or basket 25 and are provided at their outer ends with snap-hooks 32, by means of which they are detachably secured 30 to the block portions 4 or the bracket extensions 24 thereof of the said trucks. As shown, the hooks 32 engage with eyes 33, secured to the bracket portions 24.

At its inner side the car-body or basket 25 is provided with a hinged side section 34, of 35 such width and such length that when thrown downward, as best shown in Fig. 5, it may be projected into an open window, and thus constitute a platform over which a person may 40 walk from the said window to the said basket. Preferably one or more guy-ropes 35 connect the hinged side or section 34 with the side of the basket 25. Also the said side or 45 platform 34 is preferably provided with a finger or projection 36, having a down-turned end, which is adapted to engage inside of the window-sill to prevent the car from swinging outward while said platform is turned down. Turn-buttons 37 on the platform - section 34 50 are engageable with the inner side of the car or basket 25 to lock the said section 34 in its upward position, as shown in Fig. 1.

The use of the fire-escape is probably obvious from the foregoing description and 55 statements made, but may be briefly summarized as follows: Ordinarily the car or basket 25 is detached and may, as already stated, be carried with certain of the apparatus used by the fire department; but it may, 60 however, be otherwise disposed of where convenient access thereto may be had. Also the horizontal rail 23 will ordinarily be adjusted to its highest point, where it will be nearly or quite hidden by the cornice of the building. 65 Hence when the fire-escape is out of use it does not disfigure the building. In case of a fire

the rail 23 is lowered within reach from the ground, and the basket or car is attached, as already indicated and as shown in the drawings. By means of the crank 19 and wind- 70 lass connections described the rail 23 is then raised until the basket is brought to the elevation of a window from which some person or persons are attempting to escape. Usually a fireman or some other person will enter the 75 car or basket before it is raised, and such person may of course readily control the horizontal movements of said basket by pulling on one or the other of the ropes or cables 31. In this way while the basket is being raised 80 or lowered it may be moved over the rail 23, so as to reach any desired window or to escape the flames which may be issuing from any particular window. This action is important. 85

It will of course be understood that the construction above described is capable of considerable modification within the scope of my invention.

What I claim, and desire to secure by Letters Patent of the United States, is as follows:

1. The combination with a building having windows or openings at the different stories, of a fire-escape comprising a horizontal rail, a pair of windlasses operated from a common 90 source and provided with flexible connections suspending said rail from the upper portion of the building with freedom for vertical movements always in a horizontal position, truck-wheels movable on said horizontal rail, and a car or basket suspended from said truck-wheels, substantially as described.

2. The combination with a building having windows or openings at the different stories, of a fire-escape comprising a vertically-movable 105 horizontal rail, a pair of windlasses and flexible connections suspending said rail from the upper portion of the building, which windlasses are operated by a common device from near the ground, a pair of trucks movable on said rail, and a car or basket suspended from said trucks by a pair of flexible connections, substantially as described.

3. The combination with the vertical tracks or channels 2, of the trucks 4, 5, movable over 115 said tracks 2, a horizontal rail 23 secured to said trucks, the windlass-shaft 13 with wind-ing-drums 12, the flexible connections 7 connecting said drums to said vertically-movable trucks, the guide-sheaves over which said connections 120 7 run, the operating-shaft 17 with crank 19, the bevel-pinions 15 and 16 connecting said shafts 13 and 17, the trucks 26 27 movable on said horizontal rail 23, and the car or basket suspended from said trucks, substantially 125 as described.

In testimony whereof I affix my signature in presence of two witnesses.

JOHN DERUS.
